UNITED STATES PATENT OFFICE.

WILLIAM A. LORENZ, OF HARTFORD, CONNECTICUT, ASSIGNOR TO UNITED STATES HAT MACHINERY CORPORATION, OF NEW YORK, N. Y., A CORPORATION OF VIRGINIA.

MACHINE FOR SHRINKING FELT ARTICLES.

Application filed July 16, 1923, Serial No. 651,701. Renewed September 22, 1924.

To all whom it may concern:

Be it known that I, WILLIAM A. LORENZ, a citizen of the United States, and a resident of Hartford, in the county of Hartford and 5 State of Connecticut, have invented certain new and useful Improvements in a Machine for Shrinking Felt Articles, of which the following is a specification.

This invention relates to machines for 10 shrinking hat bats and the like and has as its aim to provide a machine of this sort having various features of novelty and advantage and, more particularly, which is characterized by its simplicity and cheapness in construction and its effectiveness in 15 operation.

The invention accordingly consists in the features of construction, combination of elements and arrangement of parts which will 20 be exemplified in the construction herein-after set forth, and the scope of the application of which will be indicated in the appended claims.

Other objects will be in part obvious and 25 in part pointed out hereinafter.

In the accompanying drawings, wherein I have shown, for illustrative purposes, one embodiment which the present invention may take, it being understood, however, that 30 this disclosure is by way of exemplification only and is not to be taken as restrictive of my conception;

Figure 1 is a top plan view of the machine;

Fig. 2 is a side elevation thereof;

Fig. 3 is a vertical longitudinal section taken substantially on line 3—3 of Fig. 1; and

Fig. 4 is a detail view showing the manner 40 in which the hereinafter described stripper rods may be adjusted relative to the bat carrying tapes.

Referring to the drawings in detail, the machine is provided with a frame of any 45 suitable construction, in the present instance this frame being illustrated as having a pair of side frames 10 appropriately secured together. Suitably journalled in the frame and, in the present instance, in substantially 50 the same plane, are a plurality of supporting rolls 11. Passing about these rolls are

a plurality of transversely spaced endless bat carrying tapes 12. Preferably, the rolls 11 are circumferentially grooved as at 11' so that the tapes are properly guided and 55 maintained in place and also to permit the bats, as they are carried by the tapes over these rolls, to engage these rolls. Positioned above the tapes and in interposed or staggered relation to the supporting rolls 11 are pressure or wave rolls 13 which engage the upper faces of the tapes 12 and the bats carried thereby. These pressure rollers, if desired, may be mounted for movement, under pressure, towards the tapes 12, and, to 60 this end, I have shown the opposite ends of each roll as journalled in suitable levers 14. The upwardly extending arms of these levers have attached to them springs 15 which urge the levers in such direction as 65 to force the rolls, under pressure, towards the tapes. For the purpose of preventing the bats from leaving the tapes 12 and wrapping themselves upon the wave rolls, stripper rods or wires 16 are positioned 70 lengthwise of the machine and immediately above the working run of the tapes 12 and below the axes of the wave rolls. In the 75 present instance, the opposite ends of these stripper rods are secured to cross bars 17 which, in turn, are fastened, as by means of screws or bolts 18, to the frame of the machine. These screws 18 preferably pass through elongated vertical slots 19 in the cross bars (see Fig. 4) so that these cross 80 bars, together with the stripper rods carried thereby, are adjustable. In order that the stripper rods do not interfere with the wave rolls, the latter are circumferentially 85 grooved as at 20, and the stripper rods pass 90 through these grooves as will be seen most clearly from Fig. 3. The ends of the tapes 12 pass about suitable guide rolls or drums 21. For the purpose of returning the bats after they have passed beneath the wave 95 rolls to the forward end of the machine, there are paired with the lower or return runs of the tapes 12, a plurality of similar tapes 22 supported and guided by grooved 100 guide rolls or drums 23. Preferably, the tapes 22 extend forwardly of the forward end of the tapes 12 so as to provide a bat

5 delivery position or portion from which the bats may be taken after they are passed through the machine and replaced on the forward end of the tapes 12. The supporting and wave rolls may be driven in any suitable manner as, for instance, through internemeshing gears 24.

10 The operation of the machine is briefly as follows. The bats, after they have been properly formed and sufficiently worked so as to be handled without tearing, are placed upon the forward or bat receiving end of the tapes 12 and these tapes carry the bats beneath the pressure rolls and over the supporting rolls. Owing to the fact that these rolls are in staggered relation and are urged towards each other under pressure, the bats are progressively bent to and fro and so manipulated that the fibres thereof are suitably felted and shrunk. It will be understood that the bats are maintained in a saturated condition and, to this end, water may be discharged from pipes 25 onto the bats. After the tapes 12 have carried the bats through the series of supporting and pressure rolls, the bat is returned to the forward end of the machine between the lower run of the tapes 12 and the upper run of the tapes 22. In Figs. 1 and 2, the bat, designated by the letter B, has been placed on the bat receiving portion or forward ends of the tapes 12 and is starting its passage through the machine. The bat, designated by the letter B', is shown on the bat delivery portion 30 of the tapes 22. If desired, this bat B' may be again placed on the tapes 12 for a second feeding through the machine, and this operation may be repeated as many times as is necessary to shrink and felt the bat to the 35 desired extent.

40 I claim as my invention:

1. In a machine of the character described, a plurality of supporting rolls, wave rolls arranged in staggered relation thereto, and 45 bat carrying endless tapes spaced apart transversely of the machine and passing between said supporting rolls and wave rolls.

2. In a machine of the character described, a plurality of supporting rolls, a plurality 50 of transversely spaced apart endless bat carrying tapes passing over said rolls, and wave rolls arranged in staggered relation to said supporting rolls and adapted to engage the bat carrying faces of said tapes, said 55 wave rolls being mounted for movement relative to said supporting rolls.

3. In a machine of the character described, a plurality of supporting rolls provided with 60 circumferential grooves, transversely spaced apart bat carrying endless tapes passing over said rolls in said grooves, and wave rolls interposed between said supporting rolls and above said tapes whereby the bats carried by said tapes are repeatedly bent to and fro.

65 4. In a machine of the character described,

a plurality of supporting rolls, transversely spaced apart bat carrying endless tapes passing over said rolls and returning beneath the same, wave rolls above said tapes, and means cooperating with the return or lower 70 run of said tapes for returning the bats to the forward end of the machine.

5. In a machine of the character described, a plurality of supporting rolls, transversely spaced apart bat carrying endless tapes 75 passing over said rolls and returning beneath the same, wave rolls above said tapes, and a plurality of endless tapes paired with the lower or return run of said first mentioned tapes for returning the bats to the 80 forward end of the machine.

6. In a machine of the character described, a plurality of supporting rolls, flexible bat carrying means passing over said rolls, cylindrical members engaging the bat carrying face of said means and the bats carried thereby, and stripper rods extending longitudinally of the machine for preventing the bats from winding themselves upon said 85 cylindrical members.

7. In a machine of the character described, supporting rolls, transversely spaced apart endless tapes passing over said rolls, cylindrical members engaging the bat carrying face of said tapes and the bats carried thereby, and stripper rods in fixed position above said tapes and beneath the axes of said cylindrical members, said stripper rods intersecting the peripheries of said members.

8. In a machine of the character described, a plurality of supporting rolls, flexible bat carrying means passing thereover, grooved rolls adapted to engage the bats carried by said means, and stripper rods extending longitudinally of the machine and passing 100 through the grooves in said rolls beneath the axes thereof.

9. In a machine of the character described, a plurality of supporting rolls, flexible bat carrying means passing thereover, circumferentially grooved pressure rolls interposed between said supporting rolls and adapted to engage the bats carried by said means, stripper rods positioned above the bat carrying face of said means and extending 110 through the circumferential grooves of said pressure rolls beneath the axes thereof, cross bars to which the opposite ends of said stripper rods are secured, and means for adjustably fastening said cross bars to the 115 machine.

10. In a machine of the character described, a plurality of supporting rolls, flexible bat carrying means passing thereover, circumferentially grooved pressure 120 rolls interposed between said supporting rolls and adapted to engage the bats by said means, stripper rods positioned above the bat carrying face of said means and extending through the circumferential 125

130

grooves of said pressure rolls, said rods being secured to the frame of the machine.

11. In a machine of the character described, a plurality of supporting rolls, flexible bat carrying means passing thereover, cylindrical members engaging the bat carrying face of said means and the bats

carried thereby, and stripper rods extending longitudinally of the machine for preventing the bats from winding themselves 10 upon said cylindrical member, said stripper rods being secured to the frame of the machine.

WILLIAM A. LORENZ.
